UNITED STATES PATENT OFFICE

143,150

DESIGN FOR A WALL VASE

Nona Mader, Glendale, Calif., assignor to Golden State Ceramics, Pasadena, Calif., a co-partnership

Application February 5, 1945, Serial No. 117,763

Term of patent 3½ years

(Cl. D29—28)

To all whom it may concern:

Be it known that I, Nona Mader, a citizen of the United States, residing at Glendale, in the county of Los Angeles, State of California, have invented a new, original, and ornamental Design for a Wall Vase, of which the following is a specification, reference being had to the accompanying drawing, forming part thereof.

In the drawing:

I claim:

The ornamental design for a wall vase, substantially as shown.

NONA MADER.
